S. C. BOADLE

CRAMP

Filed Sept. 12, 1925

Inventor

Sidney Charles Boadle
by Wright, Brown, Linby, May
Atlys.

UNITED STATES PATENT OFFICE.

SIDNEY CHARLES BOADLE, OF KENSINGTON, VICTORIA, AUSTRALIA.

CRAMP.

Application filed September 12, 1925. Serial No. 55,914.

To all whom it may concern:

Be it known that SIDNEY CHARLES BOADLE, a subject of the King of Great Britain, residing at 79 Bayswater Road, Kensington, 5 in the State of Victoria, Commonwealth of Australia, has invented certain new and useful Improvements in and Relating to Cramps, of which the following is a specification.

10 This invention has been devised to provide improvements in and relating to cramps, vises or the like mechanism, and is particularly useful for holding individual objects such for instance as metal plates, 15 and the invention will be described herein in reference thereto, but it is to be understood that the use of the invention is not limited thereto, as it may be employed wherever it is desired to grip and hold any 20 particular object or objects for the purposes required.

The objects of the invention are many, one of which is to provide a cramp, the parts of which are constructed and arranged 25 to enable a maximum of gripping force to be obtained by a minimum of adjusting force, and that the gripping force is applied at the opposite end to that of the adjusting force and at the other end of the instrument.

Another object of this invention is to provide a cramp, the jaws of which can be brought to the gripping position at any 30 point in their moving area with a minimum travel of the adjusting screw bolt.

Another object of this invention is to provide a cramp, the jaws of which are shaped to enable at whatever position they are set, the gripping or biting position 35 thereof will be placed to take the stress at the strongest point of each jaw.

A further object of this invention is to provide a cramp in which one of the jaws is loose on a bearing pin, and has at its 40 inner end a ratchet, being controlled by a spring pawl to enable the adjusting force to be transferred to a gripping force.

In order that my invention may be the more easily understood, reference will be 45 made to the accompanying sheet of drawings in which—

Fig. 1 is a side elevation of the cramp constructed according to my invention.

Fig. 2 is a plan view of Fig. 1 whilst—

Fig. 3 is a part sectional elevation of Fig.

1 illustrating the jaws set at a different position.

I provide an elongated member 1 of the desired dimensions to ensure the necessary strength to meet the inherent stresses and strains to which it will be subjected.

The member 1 has at one end a curved jaw 3, called the fixed jaw, the serrated end 4 of which is curved and forms a gripping or biting face. The member 1 is provided, 65 between its ends, with a fork the divisions of which are preferably formed by spaced apart ears 2, 2, integral with the member. The fork ears 2 have orifices receiving the ends of a pin 5, upon which is mounted a bifurcated lever 6, interposed between the ears 2 and extending substantially parallel with the member 1. The outer end of the lever 6 has a tapped orifice engaged with a screw bolt 7, bearing on the member 1, and adapted to exert pressure on the lever for a purpose hereinafter stated.

Mounted on the pin 5, between the divisions of the bifurcated lever 6, is a curved swinging jaw 9, having a curved serrated gripping face 4^a, opposed to the face 4. The inner or hub portion of the swinging jaw 9, and the lever 6, are provided with means for holding the swinging jaw in various positions relative to the lever, and permitting a quick adjusting movement of the jaw toward and from the fixed jaw, said means being preferably embodied in a clutch, one member of which is composed of teeth 10, forming a ratchet. The other member is a pawl 11, fixed to a pin 13, which is adapted to turn in bearings formed in the divisions of the bifurcated lever 6, the ratchet and pawl being between said divisions. The pawl is preferably held yieldingly in engagement with the ratchet by a spring 12, and may be disengaged from the ratchet by a handle or trigger 14, fixed to the pin 13.

The screw 7 constitutes a means for exerting pressure on the lever 6, to cause the latter to exert gripping force on the swinging jaw 9, through the clutch.

Before use the parts may be adjusted as shown by Figure 1, the gripping faces being closed on each other, or nearly so. The pawl is then released from the ratchet, the swinging jaw 9 is moved outward from the fixed jaw, to permit the application of the jaws to the object to be gripped, and the pawl is

allowed to again engage the ratchet. The screw 7 is now turned inward and exerts gripping pressure on the upper jaw through the lever 6, the pawl and the ratchet. The 5 releasing operation is performed by turning the screw 7 outward until the swinging jaw releases the object.

The member 1 may be provided with a shackle 15, for general hauling purposes. 10 From the above description of parts and of the operation, it will be seen that minimum adjusting force is only required to provide a maximum gripping force at the contact or biting points of the jaws, and 15 that the loose jaw can be adjusted to be placed in such a position to the object that a minimum travel of the screw bolt causes the lifting pressure of the lever arm to be transferred to the jaws providing a thorough and 20 reliable grip on the object or objects between the jaws.

Furthermore the shape and position of the jaws ensures at whatever angle they are set i. e. gripping that the stresses and strains 25 will be at the strongest point of the jaws.

It will be understood that the integral jaw may be constructed in the same manner as the other jaw, in which instance a second pawl and ratchet mechanism would be employed.

Claims—

- 35 1. A cramp comprising a member having an integral gripping jaw and a fork in which bearings are provided for a pin upon which is mounted a bifurcated lever and a loose gripping jaw with teeth, and means for controlling the movement and placing the grip on such jaws.
- 40 2. A cramp comprising a member with integral gripping jaw, a fork in which bearings are provided for a pin, a bifurcated lever mounted thereon, a loose gripping jaw

with teeth, a spring pawl mounted on a movable pin, and disposed within the bifurcation of the lever arm, a trigger fixed to 45 said movable pin, a screw bolt at the rear of the lever arm for the purpose of engaging with the member, and serrations at the contact surface of the gripping jaws.

3. A cramp comprising an elongated 50 member having at one end a fixed gripping jaw and between its ends a fork, a swinging gripping jaw pivoted to said fork and adapted to swing toward and from the fixed jaw, a bifurcated lever pivoted to the fork and to the swinging jaw, clutch means for holding the swinging jaw in various positions relative to the lever, and means for exerting pressure on the lever to cause the latter to exert gripping force on the swinging 55 jaw through said clutch means.

4. A cramp comprising an elongated member having at one end a fixed gripping jaw and between its ends a fork, a swinging gripping jaw pivoted to said fork and 60 adapted to swing toward and from the fixed jaw, a bifurcated lever pivoted to the fork and to the swinging jaw, a clutch including a ratchet formed on the swinging jaw, and a pawl pivoted to the lever, said clutch being 65 adapted to variably confine the swinging jaw against movement in one direction relative to the lever and outward from the fixed 70 jaw, and a pressure-exerting screw engaged with a tapped orifice in the lever and bearing on an end portion of the elongated member, and adapted to exert pressure on the lever to cause the latter to exert gripping force on the swinging jaw through the 75 clutch.

In testimony whereof I have signed my name to this specification.

SIDNEY CHARLES BOADLE.
